UNITED STATES PATENT OFFICE

EARL GAUSEL, OF MINNEAPOLIS, MINNESOTA

INTERNAL-COMBUSTION ENGINE

Application filed August 24, 1928. Serial No. 301,772.

This invention relates to the broad class of internal combustion engines and it has more particular reference to a number of novel structural improvements closely associated in cooperating in producing a more dependable and efficient motor.

A primary structural feature is predicated upon a distinct type of rotary cylinder valve, the same being in the form of a sleeve mounted for free rotation in a complementary cylindrical portion of the block casting, this sleeve being equipped with a worm gear receiving continuous rotary motion from a coaxial rotary worm shaft which is in turn operatively connected with the engine crank shaft through the medium of positive driving gears.

An equally important structural distinction is a peculiarly shaped lubricant conducting groove which is formed in the exterior of the cylinder valve and which is designed to automatically conduct the lubricant and to collect and maintain portions of said lubricant when the cylinder valve is at a standstill, in order to insure proper application of the lubricant the moment that the motor is started.

A further feature of construction is based upon an appropriately arranged closure in the casting in order to permit proper access to be had to the worm shaft, gears, and shaft lubricating trays or pans.

A still further structural distinction is found in the head construction of the block and associated spark plug mountings which are designed to form closures for the upper ends of the cylinders and function as guiding and retaining means for the corresponding ends of the cylinder valves.

Other features and advantages of the invention will become more readily apparent from the following description and drawings.

In the drawings:

Figure 1 is a side view of a motor constructed in accordance with the invention showing the details in section and elevation to disclose the arrangement of parts clearly.

Figure 2 is a vertical section through the structure.

Figure 3 is a horizontal section taken ap-

proximately upon the plane of the line 3—3 of Figure 2.

Figure 4 is a detailed perspective view of one of the cylinder valves.

Figure 5 is an enlarged fragmentary section showing one of the worm shaft bearings.

Figure 6 is a perspective view of an oil pan or tray associated with said worm shaft.

Figure 7 is a perspective view of a supporting bracket for the lower end structure of the cylinder valve.

Figures 8, 9, 10 and 11 respectively are horizontal sectional views through the valve and cylinder construction showing the successive positions of the valve during the intake, compression, firing and exhaust.

Referring now to the drawings by reference numerals it will be seen that the motor block is designated by the reference character 12, the head at 13, the crank case 14, the crank shaft 15, the reciprocating piston 16 and connecting rods 17. All of these parts are of conventional construction. Then, too, the exhaust and intake ports 16' and 17' are of ordinary construction and the manifold 18 is of suitable construction.

As shown in Figure 1, the motor block casting embodies open-ended stationary cylinders 19 having communicating lubricant or oil conducting ducts 20 (see Figure 1) and transverse partitions 21 (see Figure 3) shaped as shown at 24 in Figure 5 to form one-half of a bearing. At this point we also observe removable bearing caps 25 which complete the bearing structure.

The bearings formed by the parts 24 and 25 function to accommodate the journal portions 26 (see Figure 3) of the rotary worm shaft. This worm shaft is formed of longitudinally spaced threaded portions 27 and on one end of the shaft is a gear 28 in mesh with a complementary gear 29 on the crank shaft. This permits the motion to be transmitted in proper timed relation to the worm shaft. In connection with the worm shaft I wish to call attention to the provision of suitable lubricant containing trays or pans 30 properly supported for lubricating the threads of the worm portions 27. Also, opposite the shaft and the trays the casting is provided with a

longitudinal entrance opening closed by a suitably shaped closure plate 31. This permits access to be had to the worm shaft and complementary details.

Attention is now invited particularly to Figures 2 and 4. In the latter figure the reference character 32 designates a vertically disposed cylinder valve which is of tubular sleeve-like construction. This is arranged vertically in the cylinder jacket 19. It is provided at its bottom with a worm gear 33 and at its top with circumferentially spaced rectangular ports 34, 35 and 36 appropriately located for successive registry with exhaust and intake ports 16' and 17' as detailed in Figures 8 to 11 inclusive. Also, as before intimated, the exterior of the valve is grooved and embodies upper and lower annular grooves 37 and 38 and a connecting spiral groove 39. Incidentally the groove 38 communicates with the oil feed duct 20 and the lubricant is carried up to the groove 37 by the spiral connecting portion 39. The portion 39 is formed with irregular portions 40 which function as pockets which serve to collect and retain a small portion of the lubricant for effective lubricating purposes when the engine is started. The cylinder valve is arranged as shown in Figure 2 where-in it will be observed that the worm gear 33 is located opposite and in mesh with the worm shaft and is interposed between anti-friction ball bearing structures 41 and 42. The upper bearing structure abuts the castings while the lower bearing structure is supported upon suitably designed brackets 43 and 44. Access is permitted to all of these parts through the entrance opening when removing the closure plate 31. It is obvious that the cylinder or sleeve valve 32 functions additionally as a liner for the reciprocating piston 16. It is of a length to project down into the crank case with its upper end terminating in downwardly spaced relation from the corresponding end of the cylinder jacket 19.

In connection with the latter structure I call attention to the closures employed at the upper end of these parts. Each closure embodies a conical portion 45 having a central upstanding neck 46. This neck has an upper threaded end extending through an opening in the cylinder head 13, where we find a retaining ring nut 47. The neck functions as a cup for receipt of the spark plug 48. The closure also includes a marginal rim, a supporting and fastening flange and an inwardly offset portion 49 providing a guide channel and shoulder abutments for the upper end of the rotary valve.

In operation it is obvious that the worm shaft receives power in a 1 to 1 ratio from the engine crank shaft through the medium of the meshing gears 28 and 29. With this arrangement the rotary cylinder valves, of

which there may be any number, are operated at a 6 to 1 ratio. It is obvious however that the structure must be so timed as to cause the valves to rotate to occupy the approximate successive positions detailed in Figures 8 to 11 inclusive, in order that the ports 34, 35 and 36 will register in proper order with the exhaust and intake ports 16' and 17'. Reference being had to Figures 8 to 11 inclusive, the respective positions of the valve will be clear. In Figure 8 the valve registers with the fuel intake port 17'. In Figure 9 the intake port is closed during compression, in Figure 10 the intake and exhaust ports are still closed during firing and in Figure 11 the exhaust port is uncovered.

As before indicated during the rotation of the valve, oil is delivered under compression through the ducts 20 where it finds its way into the groove 38. From here it feeds automatically to the spiral portions 39 of the groove and into the top groove 37 in each valve. A limited amount of oil is retained in the pocket portions 40.

From the foregoing description and drawings it will be seen that the construction is characterized by many desirable advantages. The gear driven sleeve or cylinder valve having a ratio of 6 to 1 with the crank shaft reduces the friction by many times that of the friction produced in the conventional sleeve valve motor of today. The sleeve having a perfect rotary motion does away with any jerky action and insures positive and continuous rotation and proper intake and exhaust. A compression ratio of 5 to 1 may be obtained insuring ample power. The mounting and location of the spark plug is ideal, as is the force feed and automatic lubrication of the cylinder valve. The wear and tear is even and smooth and adds longevity to the life of the motor. The structure is characterized by unusual compactness and convenience of arrangement and there are no intricate cam shafts, tappets, pushrods, valve guides, etc. The positive mechanical opening and closing of the ports, as well as the rectangular shape providing for proper intake and exhaust, is a feature not to be overlooked.

The force feed lubrication and method of conducting it to the essential parts is a noteworthy feature. All told, it is apparent that the construction is decidedly efficient in performance, positive and dependable in action, smooth and quiet in operation, a mechanical achievement in the art and therefore capable of fulfilling the requirements of an invention of this class in an improved and suitable manner. These and other advantages and features of the invention have doubtless been made apparent and consequently a more lengthy description is regarded unnecessary.

Minor changes in shape, size and in the arrangement of parts coming within the field

of the invention claimed may be resorted to if desired.

What I claim as new is:

In an internal combustion engine of the class described, a crank case, a crank shaft mounted therein, a plurality of cylinder jackets mounted on said case, a cylindrical tubular valve mounted for rotation in each cylinder jacket and provided at one end with an operating worm gear and at its other end with circumferentially spaced equidistant rectangular ports, the intermediate exterior portion thereof being formed with spaced circumferential grooves connected by a longitudinally disposed spiral groove, having irregular shaped portions forming lubricant collecting and retaining pockets, means for operating said valves from the crank shaft, and means for establishing communication between the lower circumferential oil groove of each valve and the crank case for the purpose set forth.

In testimony whereof I affix my signature.

EARL GAUSEL.
